CLAIM

The ornamental design for a foldable portable baseboard heater, as shown and described.

DESCRIPTION

FIG. 1 is a front, top perspective view of a foldable portable baseboard heater showing my new design, the foldable portable baseboard heater being shown partially folded;

FIG. 2 is a front elevational view thereof, unfolded;

FIG. 3 is a rear elevational view thereof, unfolded;

FIG. 4 is a right side elevational view thereof, unfolded;

the left side being a mirror image of that shown;

FIG. 5 is a top plan view thereof, unfolded; and,

FIG. 6 is a bottom plan view thereof, unfolded.

FIG. 1

FIG. 4
